STANDOFF INSULATOR FOR ANTENNA LEAD-IN WIRE

Rosario J. Rizzo, Elmont, N. Y., assignor to JFD
Manufacturing Co., Inc., Brooklyn, N. Y., a cor-
poration of New York

Application November 16, 1953, Serial No. 27,604

Term of patent 14 years

(Cl. D26—14)

To all whom it may concern:

Be it known that I, Rosario J. Rizzo, a citizen of the United States, residing at 1790 Diane Street, Elmont, L. I., in the county of Nassau, and State of New York, have invented a new, original, and ornamental Design for Stand-Off Insulator for Antenna Lead-In Wire, of which the following is a specification, reference being had to the accompanying drawing, forming part thereof.

In the drawing:

Fig. 1 is a side elevational view of a stand-off insulator for television lead-in wire, showing my new design;

Fig. 2 is a front elevational view thereof.

Fig. 3 is a rear elevational view thereof.

Fig. 4 is an exploded view of the insulator and mount showing them disassembled from each other, a portion of the mount being broken away for convenience of illustration.

I claim:

The ornamental design for a stand-off insulator for antenna lead-in wire, substantially as shown and described.
